UNITED STATES PATENT OFFICE.

CORWILL JACKSON, OF KALAMAZOO, MICHIGAN.

GRINDER.

1,344,133.

Specification of Letters Patent. Patented June 22, 1920.

Application filed June 11, 1919. Serial No. 308,351.

To all whom it may concern:

Be it known that I, CORWILL JACKSON, a citizen of the United States, residing at city and county of Kalamazoo, State of Michigan, have invented certain new and useful Improvements in Grinders, of which the following is a specification.

This invention relates to improvements in grinders.

10 My improved grinder is especially designed by me as a valve grinder for internal combustion engines although desirable for use in other relations.

The main objects of this invention are,

15 First, to provide a fluid motor driven grinder which is compact and simple in structure and easily manipulated.

Second, to provide a fluid motor driven grinder in which the parts are arranged so 20 that they may be readily assembled and disassembled as occasion may require.

Further objects, and objects relating to structural details, will definitely appear from the detailed description to follow.

25 I accomplish the objects of my invention by the devices and means described in the following specification. The invention is clearly defined and pointed out in the claims.

A structure which is a preferred embodiment of my invention is clearly illustrated in 30 the accompanying drawing forming a part of this specification, in which:

Figure I is a side view of the structure embodying the features of my invention.

35 Fig. II is a detail view partially in section on a line corresponding to line 2—2 of Fig. IV.

Fig. III is a detail sectional view on a line corresponding to line 3—3 of Fig. I 40 showing details of the cylinder and rotor.

Fig. IV is a horizontal section on a line corresponding to line 4—4 of Fig. II showing details of the spindle driving means.

Fig. V is a detail section on a line corresponding to line 5—5 of Fig. II.

In the drawing similar reference characters refer to similar parts throughout the several views, and the sectional views are taken looking in the direction of the little 50 arrows at the ends of the section lines.

Referring to the drawing I provide a frame or body comprising a body member 1 having a recess-like chamber 2 on its upper side providing a gear box and a cylinder 3 on its under side. The cylinder is provided 60 with an end plate 4 detachably secured to the body member by means of bolts 5. The top member 6 is detachably secured to the body member and is provided with a hand piece 7 for the manipulation of the grinder. 65

The fluid actuated impact rotor 8 is provided with pockets 9 on its upper face. The rotor shaft 10 is supported by the bearing 11 in the end plate 4 and the bearing 12 in the wall between the rotor cylinder and the gear 70 box. The inlet passage 13 is formed in the wall between the gear box and cylinder and preferably has an annular portion 14 at its inner end delivering to the cylinder through its plurality of ports 15. 75

This inlet passage is controlled by valve 16 arranged in the bore-like casing 17 formed in the body at one side, the valve being of the plunger type and provided with an annular groove 19 adapted to be brought 80 into register with passage 14 when valve is actuated. The stem 20 of the valve is disposed through the top member 6 so as to be manipulated by the thumb of the operator while grasping the handle 7. The spring 16' 85 holds the valve normally closed. 21 represents a flexible supply pipe connected to suitable source of power.

The body member has a spindle bearing 22 disposed at one side of the cylinder. The 90 spindle 23 is provided with a blade 24 adapted to engage a valve.

The shaft 10 of the rotor projects into the gear box and is provided with pinion 25. The spindle driving gear 26 is mounted on 95 the stub shaft 27 and meshes with the pinion 25, the stub shaft being carried by the top member and disposed out of alignment with the spindle. The gear 26 has an eccentric 27 with a groove 28 on its face with which the 100 wrist pin 29 on the upper end of the spindle coacts, the wrist pin being provided with a bearing slide engaging the eccentric. Thus arranged, as the gears revolve an oscillating movement is communicated to the spindle, 105

The exhaust port 30 is also formed in the body member between the cylinder and gear box.

With this arrangement of parts I provide 5 a fluid driven grinder which is compact in structure, light in weight and conveniently manipulated.

My improved grinder is well adapted for use in garages, most of which have means 10 for providing air under pressure and many of which have no electrical power means for operating electrically driven grinders such as shown in my application, Serial No. 231,301 filed April 29, 1918. My present embodiment is an adaptation of and embodying 15 certain features of my invention shown in such application.

I have illustrated and described my improvements in an embodiment which I find 20 very practical. I have not attempted to illustrate or describe other adaptations or embodiments as I believe the disclosure made will enable those skilled in the art to which my invention relates to embody and 25 adapt the same as may be desired.

Having thus described my invention, what I claim as new and desire to secure by Letters Patent, is:

1. The combination of a body member 30 having a gear box on its upper side, a rotor cylinder on its under side and inlet and exhaust passages in the wall between said gear box and cylinder, the inlet passage having an annular portion communicating with said 35 cylinder through a plurality of ports, an end plate for said cylinder mounted on the under side of said body provided with a shaft bearing, a top member constituting a cover for said gear box provided with a hand piece, a spindle bearing at the side of said cylinder and a shaft bearing in the wall between said cylinder and gear box, an upwardly facing fluid actuated impact rotor provided with a shaft disposed in said bearings in said wall and end plate and projecting into said gear box, a pinion on said shaft, a spindle driving gear meshing with said pinion, and a valve carried by said body member for controlling said inlet passage having a stem projecting through said top member.

2. The combination of a body member 55 having a gear box on its upper side, a rotor cylinder on its under side and inlet and exhaust passages in the wall between said gear box and cylinder, the inlet passage having an annular portion communicating with 60 said cylinder through a plurality of ports, a top member constituting a cover for said gear box provided with a hand piece, a spindle at the side of said cylinder, an upwardly facing fluid actuated impact rotor provided with a shaft projecting into said

gear box, a pinion on said shaft, a spindle driving gear meshing with said pinion, and a valve carried by said body member for controlling said inlet passage having a stem projecting through said top member. 70

3. The combination of a body member having a gear box on its upper side, a rotor cylinder on its under side and inlet and exhaust passages, an end plate for said cylinder mounted on the under side of said body 75 provided with a shaft bearing, a top member constituting a cover for said gear box provided with a hand piece, a spindle bearing at the side of said cylinder and a shaft bearing in the wall between said cylinder 80 and gear box, an upwardly facing fluid actuated impact rotor provided with a shaft disposed in said bearings in said wall and end plate and projecting into said gear box, a pinion on said shaft, a spindle disposed 85 in said spindle bearing, a stub shaft mounted on said top member, a spindle driving gear on said stub shaft meshing with said pinion, and a valve carried by said body member for controlling said inlet passage 90 having a stem projecting through said top member.

4. The combination of a body member having a gear box on its upper side, a rotor cylinder on its under side and inlet and exhaust 95 passages, a top member constituting a cover for said gear box provided with a hand piece, a spindle at the side of said cylinder, an upwardly facing fluid actuated impact rotor provided with a shaft projecting into said gear box, a pinion on said shaft, a spindle driving gear meshing with said pinion, and a valve carried by said body member for controlling said inlet passage 100 having a stem projecting through said top member.

5. The combination of a body member having a gear box, a rotor cylinder and inlet and exhaust passages, an end plate for said cylinder provided with a shaft bearing, a 110 cover for said gear box, a spindle bearing at the side of said cylinder and a shaft bearing in the wall between said cylinder and gear box, a fluid actuated impact rotor provided with a shaft disposed in said bearings in 115 said wall and end plate and projecting into said gear box, a pinion on said shaft, a spindle disposed in said spindle bearing, a stub shaft mounted on said cover member, and a spindle driving gear on said stub 120 shaft meshing with said pinion.

6. The combination of a body member having a gear box, a rotor cylinder and inlet and exhaust passages in the wall between said gear box and cylinder, the inlet passage having an annular portion communicating with said cylinder through a plurality of ports, a spindle at the side of said cylinder, a fluid actuated impact rotor provided with a shaft projecting into said gear 125 130

box, a pinion on said shaft, a spindle driving gear meshing with said pinion, and a valve carried by said body member for controlling said inlet passage.

5 7. The combination of a body member having a gear box, a rotor cylinder and inlet and exhaust passages in the wall between said gear box and cylinder, the inlet passage having an annular portion communicating

with said cylinder through a plurality of 10 ports, a spindle at the side of said cylinder, a fluid actuated impact rotor provided with a shaft projecting into said gear box, a pinion on said shaft, and a spindle driving gear meshing with said pinion.

In witness whereof, I have hereunto set my hand and seal.

CORWILL JACKSON. [L.S.]
